POST FOR AN ELECTRIC FENCE

Samuel M. Shober, R.R. 2, Ireland Road,
Mishawaka, Ind.

Filed May 22, 1959, Ser. No. 815,134

3 Claims. (Cl. 256—10)

The present invention relates to a post for an electric fence.

Electric fences are commonly used for the purpose of fencing in areas in which livestock and the like are contained, these fences usually comprising a single wire charged with high voltage at low current, this wire being maintained a given distance above the surface of the ground by means of supporting posts. Heretofore, such supporting posts have been fabricated of metal, wood and plastic, and it has been found that these materials possess certain deficiencies which render their use unsatisfactory and expensive.

Metallic fence posts lack permanency in the respect that they corrode, rust and otherwise deteriorate with the passing of time. Also, it is necessary to use electrical insulators on these posts for preventing the charged wire from becoming grounded, and these insulators experience a relatively high rate of breakage. Once an insulator breaks, the charged fence wire usually contacts either the post itself or a metallic member connected to the post, which results in a short-circuit to ground. This short-circuit removes the high voltage from the wire, thereby rendering the fence ineffective in keeping livestock within restricted areas.

Maintenance of electric fences having metallic posts is relatively expensive, since as the posts deteriorate beyond a certain point, they must be replaced. Broken or damaged insulators also must be replaced.

With respect to wooden posts, not only is deterioration or rot a problem, but the wood becomes a fairly effective electrical conductor when it is wet. This conduction of electricity reduces the effectiveness of the charged fence wire, thereby reducing the voltage available for turning back livestock which may come in contact therewith. In addition to these deficiencies, unless the wooden post is quite large in cross-section, it is not as strong as it should be, the lighter wooden posts being subject to breakage under the stress of livestock bearing thereagainst or of high winds due to windstorms.

Plastic posts of the type used heretofore, while overcoming some of the defects of the metallic and wooden posts, have lacked the necessary strength and flexibility within the usual limits of practical post size and cost. Such plastic posts are subject to breakage when flexed beyond a certain point, this being due primarily to the lack of resiliency and the fragile character of the plastic materials used.

The present invention overcomes all of the foregoing deficiencies and provides a fence post having indefinite life, eliminates the need of electrical insulators, may be permanently colored for viewing at relatively great distances, is strong, flexible and resiliant, and, last but not least, is economical as to maintenance and in original manufacture and sale to the ultimate consumer.

It is therefore an object of this invention to provide a fence post for an electric fence having the characteristics just mentioned.

It is another object of this invention to provide a post for an electric fence, having extremely high corrosive resistance to the weather and soil elements normally encountered, which resistance extends the life of the post indefinitely.

Yet another object is to provide a post which requires no electrical insulators but still maintains the necessary

2

electrical insulating requirements in electric fences to a maximum value regardless of weather conditions.

Other objects will become apparent as the description proceeds.

To the accomplishment of the above and related objects, my invention may be embodied in the forms illustrated in the accompanying drawings, attention being called to the fact, however, that the drawings are illustrative only, and that specific change may be made in the specific constructions illustrated and described so long as the scope of the appended claims is not violated.

In the drawings:

FIG. 1 is a side elevation of an embodiment of this invention;

FIG. 2 is a top or end view thereof;

FIG. 3 is a sectional illustration taken substantially along section line 3—3 of FIG. 1;

FIG. 4 is a diagrammatic illustration of the fence post of the preceding figures properly mounted for supporting an electric-fence wire;

FIG. 5 is an illustration of another embodiment of this invention;

FIG. 6 is a fragmentary illustration shown partly in section of the embodiment of FIG. 5;

FIG. 7 is a top plan view showing a fence wire clamped in position in the embodiment of FIG. 5;

FIG. 8 is an illustration of still another embodiment of this invention; and

FIG. 9 is a side view of the embodiment of FIG. 8 with a fence wire clamped in position.

Referring to the drawings, the fence post comprises a solid, elongated rod 10 which is fabricated of an elongated bundle of glass threads imbedded in and thoroughly impregnated with a suitable, hardened resinous material such as a polyester resin. The glass threads are stretched or tensioned and are maintained in this condition by the hardened resinous material, this tensioning being important from the standpoint of providing the necessary strength, resiliency and flexibility in the finished rod. Without the glass thread being so tensioned, the finished rod is relatively weak, non-resilient and non-flexible, and otherwise is unsatisfactory as a post for use in connection with electric fences.

The rod 10 is preferably fabricated in accordance with the disclosure of Meek Patent #2,684,318, issued July 20, 1954, and entitled "Method and Apparatus for Fabricating Glass Rod," or, further, may be made according to the usual techniques involved in the manufacture of the popular, solid, glass-reinforced-plastic fishing rods.

To the upper end of the rod 10 is fastened a metallic eyelet 12 which is composed of a short length of steel wire which is stiff enough for maintaining the electric-fence wire in supported position. This wire has one end portion tightly coiled at 14 around the rod 10, this coil 14 being so tight as to fasten securely the eyelet to the rod. The other end portion of the wire is bent into an enlarged, substantially closed loop 16, and as shown in FIG. 2 need not be completely closed and may be in the form of a one-turn helix. This loop is joined to the coil 14 by a straight portion 18 which extends laterally from the rod 10. The loop 16 also is aligned vertically and may thus be said to lie in a plane substantially parallel to the rod 10. Also, the loop depends from the straight portion 18, thereby providing a natural support or retainer for the charged fence wire passed therethrough.

Intermediate the ends of the rod 10 but positioned more closely to the lower than the upper end of the rod is a step member, indicated generally by the reference numeral 20. This member 20 is also formed of relatively stiff and strong steel wire which is fastened at its opposite

ends to spaced points on the rod 10 by means of the two helical coils 22 and 24, respectively. These coils 22 and 24 are wrapped so tightly about the rod as to provide a secure fastening. Extending radially outwardly from the coil 22 and constituting an extension thereof is a horizontal step portion 26 which is joined at its outer end by means of a supporting section 28 which extends downwardly and inwardly to join the coil 24.

The eyelet 12 as well as the step 20, may be fabricated of any suitably strong steel or aluminum wire, Nos. 6 and 8 gauge steel wire serving quite satisfactorily. For convenience in inserting the rod 10 into the ground, the lower end is pointed, as indicated by the numeral 30 in FIG. 1.

In use, the rod 10 is forced into the ground as shown in FIG. 4 by placing the foot on the step portion 26 of the step member 20 and forcing the rod downwardly to a suitable depth. Preferably, the rod is driven into the soil to a depth at which the step portion 26 is flush with the ground surface. At this depth, the step serves as a stabilizing member for holding the post upright against lateral stresses. A suitable wire 32 constituting the charged fence wire is threaded through the eyelets 12 on the upper ends of the rods 10. To this wire 32 is connected a source of high voltage at low current, one side of this source being grounded as shown. Thus, any animal which while standing on the soil comes into contact with the wire 32 obtains a shock through the circuit including the wire 32 and the soil.

A second embodiment of the invention is illustrated in FIGS. 5, 6 and 7. Like numerals indicate like parts. In this embodiment, instead of using eyelets 12 formed of wire for retaining the charged conductor 32 in place, a spring clip, indicated generally by the numeral 36, is used. This clip is fabricated of a strip of spring steel preformed substantially to a V-shape, the extremities 38 and 40 thereof being formed with apertures 42 and 44, respectively, which are aligned along an axis substantially normal to a bisector of the clip angle. These apertures 42 and 44 receive the rod 10 therethrough, and the preset resilience of the clip tends to spread the extremities 38 and 40 apart into frictional gripping engagement with the rod.

The apex portion of the clip is enlarged and part cylindrical in shape, as indicated by the numeral 46, this cylindrical portion serving as a retainer for a fence wire 32 as illustrated in FIGS. 6 and 7. The sizes of the apertures 42 and 44, the angle between the two extremities 38 and 40, and the size of the retainer 46 are such that when the fence wire 32 is fitted into the retainer portion 46, the latter securely clamps the fence wire in position and the extremities 38 and 40 firmly engage the rod 10. The extremities 38 and 40 are forcefully urged apart due to the inherent resilience of the clip itself as well as the presence of the wire 32 in the retainer portion 46 whereupon the clip is firmly locked in position on the rod 10. If it is desired to change the position of the clip on the rod, it is only necessary to pinch or compress the extremities 38 and 40 toward each other an amount sufficient to release the engagement with the rod 10, thereby permitting the clip to be moved on the rod to a desired position.

The use of this clip 36 is important for the reason that it not only permits a ready adjustment of the supported height of the fence wire 32, but permits the tensioning of the fence wire from post to post as the fence is being installed. This eliminates the need of a fence stretcher which normally is required to tighten the fence wire before it is finally secured in place.

In FIGS. 8 and 9 are illustrated still another embodiment of this invention, wherein like numerals again indicate like parts. This embodiment differs from that shown in FIGS. 5-7 in the respect that the apex portion of the clip is formed with two outwardly extending spaced apart, parallel sides 48 and 50, respectively, which are

joined at the outer ends thereof by a spring section 52. As shown in FIG. 9, when a wire 32 is clamped between the two sides 48 and 50, and this wire 32 is larger in diameter than the spacing between the two sides, the latter form inwardly at 54 to a spacing which is smaller than the diameter of the wire 32. By this means, the wire 32 is securely clamped in position and is held against movement either longitudinally or laterally.

Since the post 10 is fabricated of glass and resinous material, it is, for all practical purposes, non-corrosive. It therefore has an indefinite life and requires no maintenance or servicing. Since the glass and resinous material constituting the posts are good dielectrics, or, in other words, are electrical insulators, it is not necessary to use any type of specially made electrical insulator as is true in the case in which metallic and wooden posts are used. Instead, this invention uses a metallic retainer or clamp 12, 36 fastened to the top of the post for holding the charged fence wire 32 in position. The particular retainers or clamps of FIGS. 1, 5 and 8 as already described are extremely simple in design and require no maintenance or servicing after being installed.

By reason of the glass threads in the rod 10 being under tension, the rod is resilient and flexible and can be curved to the extent of touching the ground without breaking. This is important inasmuch as violent winds cannot break or permanently deform the posts, as is true in the cases in which metallic and wooden posts are used.

The rod 10 is inexpensive, strong, and requires only the simplest of fixtures for completing the post assembly. This simplicity of construction conduces to economy of manufacture, which economy is reflected in the relatively low cost at which the post may be sold and installed.

What is claimed is:

1. An electric-fence post comprising an elongated rod composed of a bundle of elongated glass threads under tension imbedded in and bonded together by a solidified resinous material, said rod being of circular cross-section and provided with a point on its lower extremity; a metallic eyelet secured to the upper end of said rod and comprising a length of stiff wire having opposite end portions, one end portion being coiled tightly around said rod to fix said length of wire thereto, the other end portion of said length of wire being formed into an enlarged helical coil of one turn which extends in a plane substantially parallel to said rod; a step secured to said rod intermediate the ends thereof, said step comprising a second length of stiff wire having opposite end portions tightly wrapped around said rod at spaced apart portions thereon, said second length extending radially outwardly from the upper end portion and angling downwardly to the lower end portion, whereby said rod may be driven into the earth by a downward force on said step.

2. An electric-fence post comprising an elongated rod composed of a bundle of elongated glass threads under tension imbedded in and bonded together by a solidified resinous material; a metallic eyelet secured to the upper end of said rod and comprising a length of stiff wire having opposite end portions, one end portion being coiled tightly around said rod to fix said length of wire thereto, the other end portion of said length of wire being formed into an enlarged helical coil of one turn which extends in a plane substantially parallel to said rod; a step secured to said rod intermediate the ends thereof, said step comprising a second length of stiff wire having opposite end portions tightly wrapped around said rod at spaced apart portions thereon, said second length extending radially outwardly from the upper end portion and angling downwardly to the lower end portion, whereby said rod may be driven into the earth by a downward force on said step.

3. An electric-fence post comprising an elongated rod composed of a bundle of elongated glass threads under tension imbedded in and bonded together by a solidified resinous material; a metallic eyelet secured to the upper

end of said rod and comprising a length of stiff wire having opposite end portions, one end portion being coiled tightly around said rod to fix said length of wire thereto, the other end portion of said length of wire being formed into a loop which extends in a plane substantially parallel to said rod; a step secured to said rod intermediate the ends thereof, said step comprising a second length of stiff wire having opposite end portions tightly wrapped around said rod at spaced apart portions thereon, said second length extending radially outwardly from the upper end portion and angling downwardly to the lower end portion, whereby said rod may be driven into the earth by a downward force on said step.
